COMBINED BOTTLE AND DISPLAY CONTAINER THEREFOR

Jay Doblin, Chicago, Ill., assignor to The Gillette
Company, Boston, Mass.

Filed Oct. 13, 1969, Ser. No. 19,545

Term of patent 14 years

Int. Cl. D9—01

U.S. Cl. D9—12

FIG. 1

FIG. 2

FIG. 1 is a view in front elevation of a combined bottle and display container therefor showing my new design; and

FIG. 2 is a top view.

The rear and sides are identical in appearance to the front.

I claim:

The ornamental design for a combined bottle and display container therefor, as shown and described.
